UNITED STATES PATENT OFFICE.

HENRY A. BURKHART, OF FITZGERALD, GEORGIA.

PERMUTATION LOCK.

Application filed February 14, 1924. Serial No. 692,808.

To all whom it may concern:

Be it known that I, HENRY A. BURKHART, a citizen of the United States, residing at Fitzgerald, in the county of Ben Hill and State of Georgia, have invented a new and useful Permutation Lock, of which the following is a specification.

The present invention relates to locks and more particularly to locks of the permutation type.

The primary object of the invention is to provide novel means to insure an accurate and precise movement of the dogs that operate with the tumblers of the lock so that a fine adjustment of the locking dogs with respect to the tumblers, may be made.

Another important object of the invention is to provide means for automatically disconnecting the dog controlling knobs and the dog operating links preventing reverse movement thereof to insure against a person forcing the lock to operate the same.

A further object of the invention is to provide means operating in conjunction with the controlling knob for restricting movement thereof and insure against accidental movement of the controlling rod when the dog controlling rods are being manipulated.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an end elevational view of a lock constructed in accordance with the invention.

Figure 2 is a sectional view taken on line 2-2 of Figure 1.

Figure 3 is a sectional view taken on line 3-3 of Figure 1.

Figure 4 is a sectional view taken on line 4-4 of Figure 2.

Figure 5 is a fragmental plan view disclosing one of the dog operating knobs.

Figure 6 is a side elevational view of one of the dog operating knobs, a portion of the frame being shown in section.

Figure 7 is an elevational view with one of the plates of the frame being removed.

Figure 8 is an elevational view disclosing

the knob locking finger in its inactive position.

Figure 9 is a sectional view taken on line 9-9 of Figure 5.

Figure 10 is a plan view, the two upper plates of the lock casing being removed to illustrate the manner of setting the dials of the lock.

Figure 11 is a bottom plan view of one of the tumbler disks.

Figure 12 is a side elevational view of one of the stationary tumblers.

Figure 13 is a side elevational view of one of the movable tumblers.

Figure 14 is a fragmental detail view disclosing, a dog supporting plate and dog carried thereby.

Figure 15 is a perspective view of one of the dog locking arms.

Figure 16 is a fragmental sectional view disclosing the movable carriage supports.

Figure 17 is a fragmental detail of the tumbler carriage.

Referring to the drawings in detail, the reference character 5 designates the base plate of the lock, while the plate indicated at 6, and which is secured to the base plate 5 as by means of the posts 7, provides the upper plate of the lock. Supported between the plates 5 and 6, are a plurality of arms 8 which have right angled lower extremities 9 apertured to accommodate screws 10 that have their threaded extremities disposed in suitable openings in the plate 5 to secure them in position.

The upper ends of the arms 8 have connection with the frame 11 as through the screws 12, which frame 11 provides a support for the movable dogs 13 to be herein-after more fully described and which are constructed to move transversely of the frame.

Supported between the arms 8 are the bracket members 14 formed with grooves to accommodate the side bars of the locking carriage 17. Supported directly under the tumbler locking carriage is a tumbler carriage indicated at 18, which is constructed and mounted so that the carriages 17 and 18 may move with respect to each other. Mounted under the frame 11 is a movable frame 21 designed to carry the pivoted dog locking arms 22 that

are provided with teeth 23, which teeth 23 cooperate with the teeth 24 formed on the adjacent edges of the dog supporting plates

25 which plates support the dogs 13 in a manner to permit the same to move transversely of the frame in which they are supported to bring the dogs into registry 5 with predetermined tumblers.

Each of these dog locking arms includes a rearwardly extended finger 22' which is engaged by a coiled spring 23' carried by the frame 21 on which the pivoted dog 10 locking arms are mounted so that the dog locking arms will be normally tilted forwardly into engagement with the teeth of the members 25.

Forming a part of the carriage 18 are 15 the upwardly extended arms 26 formed with openings to accommodate the shafts 27 on which the tumblers 28 and 29 are supported. The tumblers 28 and 29 are arranged in sets, there being provided one set 20 of tumblers for each sliding dog so that it is necessary to move the sliding dogs into registry with movable tumblers of the sets, to permit the carriages to move and accomplish the movement of the sliding bolt 30.

25 The tumblers 29 are stationary so that should the dogs associated therewith be moved to positions in the paths of travel of the stationary tumblers, the movement of the carriages to operate the bolt 30 would 30 be prevented.

Coiled springs 31 have connection with the pivoted tumblers 28 for moving the tumblers to their normal positions after the locking carriage has moved to release the tumblers which have been previously actuated. The tumbler locking carriage is provided with tumbler engaging bars 32 that are disposed at oblique angles with respect to the side bars 16 and arranged with respect 40 to the tumblers so that the bars will move over the fingers 33 of the tumblers that are shown as extending forwardly therefrom to hold the tumblers which have been moved to their inactive positions, against movement temporarily to their active positions.

45 The lower ends of the tumblers 29 are formed with notches 36 adapted to accommodate the transverse ribs 35 that extend upwardly from the tumbler carriage whereby the tumblers 29 are locked against pivotal movement on the shafts supporting them.

Pivotedly supported at one end of the frame 11 and at opposite sides thereof are arms 37 that have their upper ends extending into suitable openings formed in the locking frame 21, so that when the carriages 17 and 18 are moved towards one end of the lock the carriage 18 will contact with the lower ends of the arms 37 moving the upper ends thereof in reverse directions, with the result that the teeth of the locking arms 22 move from engagement with the teeth of the dog supporting plates 25, releasing the dogs for free transverse movement.

50 Extending downwardly from the tumbler

carriage 18 is a pin 41 which is engaged by the forked end 42 of the bell crank lever 43 that is pivotally supported by the plate 5 of the lock frame.

The opposite arm of the bell crank lever 70 which is indicated at 44 has connection with the sliding bolt 30 as at 45 so that when the carriage 18 is moved longitudinally of the plates, the bolt 30 is moved laterally from the lock frame to cause the same to enter 75 its keeper or move to its unlocked position.

A vertical shaft 46 is disposed between the plates 5 and 6 and carries the pinion 47 at its lower end, the pinion 48 being carried 80 at its upper end. The pinion 47 is in mesh with the teeth 49 formed on one of the flanges 19 of the tumbler carriage 18 so that as the shaft 46 rotates, movement is imparted to the tumbler carriage 18 to move the tumbler carriage and tumblers supported thereby. Supported on the under surface of the plate 6 is a pinion 50 which is in mesh with the pinion 49', the pinion 50 supported by the shaft 51.

85 This pinion 50 meshes with the pinion 52 mounted on the shaft 53 that forms a support for the controlling knob 54. Thus it will be seen that as the pinion 52 operates, a relative movement is imparted to the pinion 48 to operate the tumbler carriage 18 95 which as before stated, operates the sliding bolt 30.

90 Supported adjacent to the pinion 52 and secured to the shaft 53, is a disk 55 provided with notches 56 disposed in the periphery thereof and arranged in spaced relation with each other as clearly shown by Figure 3 of the drawings, which notches are designed to receive the lugs 57 of the spring arms 58 that are pivotally supported at 58' to normally hold the shaft 53 against movement.

95 Extending through the plate 6 are the dog operating shafts 59, 60, 61 and 62, which 110 shafts 60 and 62 support pinions 63 and 64 respectively, while the shafts 59 and 61 support disks 65 through a clutch mechanism to be hereinafter more fully described. Each of these disks 65 is formed with a heart-shaped cam groove 66, in which the pins 67 of the dog operating links 68 move, when the disks are rotated.

115 Each of the clutch members employed for connecting the dog controlling knobs to the disk associated therewith includes a circular member 69 formed with a threaded extension 70 fitted in a threaded opening in the knob associated therewith, as clearly shown by Figure 9, a set screw 71 being provided to secure the member 69 against movement when the knob is being rotated.

120 Forming a part of the member 69 is a flange 72 that fits under the plate 73 and is held in position by the plate. Carried by the member 69 is a pivoted pawl 74 formed

with an extension 75 adapted to move over the cam surface 76 of the ring member 77 that is supported adjacent to the member 69, the members 69 being surrounded by the members 77. The members 77 are held in position by means of the plates 78 that are secured to the under surface of the plate 73 by means of screws 79, whereby movement of the ring member 77 will be permitted.

Disposed under the member 69 is a disk 80 formed with a plurality of teeth 81 that cooperate with teeth of the disk member 82 to which the disk members 65 are secured, the shaft on which the disk is supported being threaded at 82' to move in suitable threaded openings of the disks associated therewith. Thus it will be seen that due to this construction, the disks 65 may be adjusted with respect to the disks 80 associated therewith to change the combination of the lock and the relation of the disks with respect to each other.

Carried by each of the disks 80 is a lug 83 that is adapted to cooperate with the pivoted pawl 74 associated therewith so that when the pivoted pawl is rotated in the direction of the arrow as shown by Figure 7 of the drawing, the combination between the knobs and disks 65 will be made, to the end that the knobs may be continuously rotated without affecting the rotations of the disks. Upon movement of the knobs in the opposite direction, it will be seen that the pawls will move outwardly, due to their movements over the cam surfaces of the ring members 77, and due to the fact that the lugs 83 lie within the paths of travel of the pawls 74 the disks will be picked up and carried with the pawls, resulting in a relative movement of the dog actuating links 68.

Pinions 63 and 64 also operate in conjunction with clutch mechanisms as described for operating the disks 84 that carry gears that are connected to the circular members 69 thereof, whereby a rotary movement of the knobs rotating the pinions 63 and 64 may be permitted in one direction without affecting the movement of the disk 84 carrying the cam groove associated therewith, while upon movement of the pinions in the opposite directions, the disks 84 will be rotated to operate the dog actuating links associated therewith.

The dog operating links 68 are pivotally supported at 85 and have arms 86 pivotally connected at their free ends, which arms have pivotal connection with the dog supporting plates 25 so that movement of the links 68 results in a movement of the plates 25 transversely of the lock frame.

Mesning with the pinion 52 of the controlling knob shaft, is a pinion 87 that meshes with a pinion 88 carried on the

upper end of the shaft 89 which shaft 89 supports the pinion 90 at its lower end, which pinion is formed with an elongated opening 91 that accommodates the pin 92, carried by a disk 90' supported directly under the pinion 90 and which is secured to the shaft 89 so that the disk will be permitted to move until the pin contacts with one wall of the elongated opening, whereupon the disk picks up the pinion to rotate the pinion 90 which is in mesh with the teeth of the locking carriage 17.

From the foregoing it will be seen that on moving the carriages to bring the locking carriage 17 to a position where the tumbler engaging bars may move under the tumblers to lock the same in their inactive positions, it is necessary to move the tumbler supporting carriage slightly in advance of the locking carriage, which movement is permitted by the connection between the disk 90' and pinion 90 as described. In order that the frictional contact between the disk 90' and pinion 90 will not cause a movement of the pinion 90, a disk 93 is secured to the pinion 90 on the upper surface thereof, which disk 93 is formed with notched portions 94 that are engaged by the lugs 95 of the spring arms 96 pivotally connected to the lock frame at 97. Thus it will be seen that due to this construction, in order to move the pinion 90, it will be necessary to overcome the tension of the arms 96 to cause the lugs 95 to move from the notched portions.

Each dog controlling knob is provided with graduations 98 which are adapted to line up with a suitable marking provided on the plate supported under the knob, the plate 99 supported thereabove, being supplied with openings to receive the knobs.

In the operation of the device, the dog operating knobs are operated to bring the dogs to predetermined positions in the paths of travel of certain pivoted tumblers, whereupon the controlling knob is operated to move the tumbler carriage longitudinally of the lock frame to slide the bolt to its active position.

After the bolt has been moved to its active position, the dog operating knobs may be moved to move the dogs from their positions adjacent to the tumblers which have been actuated. It is obvious that when the dogs have been moved and have assumed a position on the opposite sides of the tumblers, the locking carriage moves to lock these tumblers in their inactive positions.

In order to move the sliding bolt to its inactive position, it is necessary to rotate the dog actuating knobs to move the dogs to positions aligning with the tumblers which have been moved to their inactive positions, whereupon the controlling knob may be

operated to slide the tumbler carriage to its initial position with the result that the sliding bolt moves within the lock frame.

I claim:

5. 1. In a lock construction, a frame, a tumbler carriage mounted for sliding movement within the frame, transversely movable dogs mounted within the frame and adapted to move in the paths of travel of the tumblers, 10 a link for operating each dog, disks having heart-shaped grooves, said links having pins adapted to move in the grooves for transmitting movement of the disks to the links, means for operating the disks, and a sliding bolt operated by the movement of the tumbler carriage.
2. In a lock construction, a frame, a tumbler carriage mounted within the frame, and adapted to be moved longitudinally thereof, 15 sets of tumblers on the tumbler carriage, transversely movable dogs mounted on the frame and adapted to be moved in the paths of travel of the tumblers, disks supported by the frame, said disks having grooves, 20 link members having pins movable in the grooves, means for connecting the link members and dogs, and a sliding bolt operated by the movement of the tumbler carriage.
3. In a lock construction, a frame, a tumbler carriage mounted for sliding movement within the frame, tumblers on the tumbler carriage, dogs movable transversely of the frame and adapted to be moved to positions in the paths of travel of the tumblers to allow movement of the tumbler carriage, disks having grooves of irregular formation, link members having pins movable in the grooves and having connection with the dogs to move the dogs, and a sliding bolt movable with the tumbler carriage.
4. In a lock construction, a frame, a tumbler carriage movable within the frame, dogs adapted to move to positions adjacent to the tumbler carriage, disks having 45 grooves, link members connecting the dogs and disks, said link members having pins movable in the grooves, controlling knobs for moving the disks, and means for clutching the controlling knobs to the disks.
5. In a lock construction, a frame, a tumbler carriage movable longitudinally of the frame, dogs cooperating with the tumbler carriage to permit of movement of the tumbler carriage, disks supported by the frame, means for connecting the dogs and

disks to cause the dogs to move when the disks are rotated, operating knobs for the disks, and means for connecting the knobs and disks to permit of movement of the knobs in one direction independently of the disks.

6. In a lock construction, a frame, a sliding tumbler carriage mounted within the frame, dogs for controlling the movements of the tumbler carriage, disks supported by the frame, means for connecting the disks and dogs to transmit movement of the disks to the dogs, a pair of disks mounted on each of the first mentioned disks, a lug carried by one of the latter disks, a ring member loosely mounted above the disks and having an extension, an operating knob for each of the first mentioned disks, a pivoted pawl carried by each knob and adapted to co-operate with the extension and lug to clutch the knobs and disks together for moving the link members.

7. In a lock construction, a frame, a sliding tumbler carriage mounted within the frame, tumblers carried by the tumbler carriage, movable dogs associated with the tumblers and adapted to move in the paths of the tumblers to restrict movement of the tumbler carriage, link members, means for connecting the link members and dogs, 85 disks associated with the link members to operate the link members, operating knobs associated with the disks, one of said disks having an upwardly extended lug, a rotatable ring member surrounding the lug, and means carried between the ring member and lug and operated by movement of the knob associated therewith for connecting the knob and disks, and said means adapted to release the disks when the knob associated therewith is moved in one direction.

8. In a lock construction, a sliding carriage, tumblers mounted on the sliding carriage and adapted to actuate a sliding bolt, a controlling knob for moving the sliding carriage, a disk rotatable with the controlling knob and having cut out portions, spring arms having lugs adapted to move into the cut out portions to normally restrict movement of the controlling knob and means for locking the tumbler carriage against movement.

In testimony that I claim the foregoing as my own, I have hereto affixed my signature.

HENRY A. BURKHART.
